(Cl. D86—10)

To all whom it may concern:

Be it known that I, Eric Leopold Hugo Cosby, a subject of the King of Great Britain, residing at London, England, have invented a new, original, and ornamental Design for a Combined Shaving Bowl and Styptic Pencil Holder, of which the following is a specification, reference being had to the accompanying drawings, forming a part thereof.

I claim:

The ornamental design for a combined shaving bowl and styptic pencil holder, as shown.

ERIC LEOPOLD HUGO COSBY.
